ATTORNEY.

UNITED STATES PATENT OFFICE.

THOMAS C. CRAIG, OF WATERBURY, CONNECTICUT.

ELEVATOR.

Application filed August 24, 1920. Serial No. 405,587.

To all whom it may concern:

Be it known that I, THOMAS C. CRAIG, a citizen of the United States, residing at Waterbury, Connecticut, have invented certain new and useful Improvements in Elevators; and I do hereby declare the following to be a full, clear, and exact description of the invention, such as will enable others skilled in the art to which it appertains to make and use the same.

This invention relates to an elevator, and one designed especially for passenger use, but being adapted also for use as a freight elevator.

15 A primary object is to provide an elevator car with driving mechanism mounted directly thereon, said mechanism cooperating with engaging devices mounted in the elevator shaft.

20 A further object is to provide an electrically driven car, the driving mechanism being of the worm type and of special construction as hereinafter specified.

25 A still further object is to provide in connection with an electrical controlling device of the usual construction, means for throwing out the trolley elements and applying a brake to the driving shaft, in one operation.

30 With the foregoing and other objects in view, the invention consists in the novel construction, combination, and arrangement of elements hereinafter described and claimed.

In the drawings:

35 Figure 1 is a view showing the elevator car in elevation, and showing that portion of the shaft structure mounting the vertical rack bars.

40 Figure 2 shows the car in top plan and the shaft structure in transverse section.

Figure 3 is a top plan view of the driving mechanism, located beneath the floor of the car.

45 Figure 4 is a section through the gear casting of Figure 3 and transversely of the worm shafts.

Figure 5 is a detail view showing a brake wheel and a shoe thrown into engagement therewith by a cam mounted on a transverse shaft.

50 Figure 6 is a diagrammatic view of the devices controlling the motor and effecting connection with the trolley wires.

Figure 7 is a fragmentary view, in elevation, showing another form of drive. 55

Figure 8 is a top plan view of the mechanism shown in Figure 7.

The shaft structure includes a plurality of uprights 10 and 12 connected by plate members 14 on the inner side of which are 60 the guiding elements for the car and the propelling mechanism. The car includes a floor 15, a top 16, an upper transverse member 17 and side structural elements 18 and 19 connected respectively with the floor and 65 with the transverse member 17.

Vertical guides 20 and 21 are mounted on the vertical plate member 14, and cooperate with a guiding member 22 on each end of the transverse element 17. The driving 70 shaft referred to below is mounted in bearing blocks which also operate in vertical guides 20 and 21. This structure is duplicated on the opposite side of the shaft, and provision is there made for supporting the 75 trolley wires.

A rack 24 is mounted between the guiding elements 25 and is suitably spaced from the guides 20 and 21 so that the gear wheels 26 on each end of the driving shaft may 80 mesh with the rack, the radius of the gear wheels being equivalent to the distance between this shaft and the rack 24.

A gear case 29 is suspended beneath the floor of the car and is provided with bearing elements for the several shafts about to be referred to. The motor 30 is mounted on the wall of the casing 29 on the car and drives shaft 31 carrying beveled pinions 32 and 33, the latter driving beveled gear

90 wheels 34 and 35 on worm shafts 36 and 37. The drive for worm shaft 37 is through gear wheel 33, rear wheels 33', 33'' carried by the short shaft shown by dotted lines in Figure 4, and thence through gear wheel 35.

The worms 38 and 39 mesh with worm wheels 40 and 41 mounted on the driving shaft 42, and the latter carries a gear wheel 26 on each end thereof. The gear wheels just referred to mesh with the racks 24

100 previously mentioned, and impart movement to the car in either direction, depending upon the direction of rotation of the motor shaft. The worm gearing acts as a locking device and prevents the descent of the car when the current is cut off from the

motor, but independent braking mechanism is also provided.

Depending from the floor of the car are two braces 44, each mounting a box 45 for 5 the driving shaft 42.

Conducting wires, or trolley wires, 46 and 47, are suitably installed on one side of the shaft, and trolley wheels 48 and 49 cooperate therewith, and are mounted on a swinging 10 trolley bracket or the like shown at 50. The bracket 50 is under the control of the brake lever, having connection by means of a link 51 with a crank 52 on shaft 53 rocked by arm 54 which has pivotal connection with a 15 link 55, and the latter has connection with a brake lever 56. This lever 56 also has connection with a rod 57 pivoted to a crank 58 on a rock shaft 59, the latter having a cam element 60 serving to cause the brake 20 shoe 61 to engage the brake wheel 63. The brake wheel is mounted on the driving shaft 42, and the lever connections just described serve the double purpose of throwing the trolley wheels away from the conducting 25 wires and applying the brakes. It is also apparent that upon the release of the brake the trolley wheels are thrown to operative position. The lever 65 of the controller 66 serves the usual purpose, the speed of the 30 motor being governed by the controller.

The propelling means above described is designed especially for use on passenger elevators, and a type of driving mechanism for use particularly on freight elevators will 35 now be described.

In Figure 10 an electric motor 100 drives the shaft 101 carrying a spiral worm 102, the engaging elements of which are constructed and proportioned to mesh with the 40 spiral gear wheels 103, the latter in turn meshing with a large gear wheel 104 mounted on a shaft 105, and the smaller gear wheel being mounted on shaft 106.

The shaft 105 has shoes 105' cooperating 45 with guides 107, and the shaft 106 carries shoes 106' cooperating with guides 108 extending vertically within the elevator shaft. The rack bars are shown at 109 and 110. In 50 referring to the gear wheels and the shafts on which they are mounted it will be observed that there are two transverse shafts on each side of the motor and between the latter and the racks, and that each shaft 55 carries two gear wheels, two rack bars being provided for the two large gear wheels on the shaft 105.

What is claimed is:—

1. The combination with an elevator car and driving mechanism mounted thereon, 60 said mechanism including a shaft extending transversely of the car, a brake wheel on

said shaft, a shoe for engagement with the brake wheel, a lever mounted on the car, and means connecting the lever and the shoe for operating the latter, such driving mechanism including an electric motor and a circuit 65 therefor, and means connected with said lever for breaking the circuit and applying the brake simultaneously.

2. The combination with an elevator car 70 and driving mechanism carried thereby, said mechanism including an electric motor, a circuit for said motor, a controller connected with said circuit and said car, conducting 75 elements adapted to be mounted in the elevator shaft, a swingingly mounted trolley bracket carried by the car, wheels mounted on the bracket and adapted to engage the conductors when the bracket is swung to operative position, a lever and means connected therewith for controlling the movement of the bracket, a brake for the driving mechanism and means operatively connected with the brake and with the lever effecting the application of the brake when the lever 80 is thrown to position for throwing the bracket, and the contact making wheels carried thereby to inoperative position.

3. In combination with an elevator car 85 and driving mechanism carried thereby, said mechanism including an electric motor, a circuit for said motor, a controller connected with said circuit and said car, conducting elements adapted to be mounted in the elevator shaft, a swingingly mounted 90 trolley bracket carried by the car, wheels mounted on the bracket and adapted to engage the conductors when the bracket is swung to operative position, a lever, a rod having a terminal crank, a link connected at 100 one end to said crank and having its outer end connected to said bracket, a second link connected at one end to a rod, and a third link connected with one end to said lever and at its other end to the second link, 105 whereby said bracket is swung to operative or inoperative position on movement of said lever; a brake for the driving mechanism, said brake comprising a brake wheel mounted on a drive shaft, a brake shoe, to 110 cooperate with said brake wheel, and links connecting said brake shoe and lever, whereby when said bracket is moved to break the circuit of the motor, said brake will be automatically applied.

In testimony whereof I affix my signature in presence of two witnesses.

THOMAS C. CRAIG.
